UNITED STATES PATENT OFFICE.

WILLIAM EDWARDS, OF WINNIPEG, MANITOBA, CANADA.

SAFETY LOCK-SHOE FOR RAILS.

1,099,288.

Specification of Letters Patent.

Patented June 9, 1914.

Application filed September 29, 1913. Serial No. 792,398.

To all whom it may concern:

Be it known that I, WILLIAM EDWARDS, of the city of Winnipeg, in the Province of Manitoba, Canada, have invented certain new and useful Improvements in Safety Lock-Shoes for Rails, of which the following is the specification.

The invention relates to an improvement in safety lock shoes for rails and the object 10 of the invention is to provide a simply constructed easily applied shoe which will receive and effectively hold a rail, the shoe being arranged in such a manner that it not only strengthens or reinforces the rail but 15 also prevents the rail from being displaced laterally.

A further object of the invention is to provide in combination with the shoe a tie for receiving and holding the shoe.

With the above objects in view the invention consists essentially in a metallic tie having suitable recesses located in the upper face thereof and provided on the under side with extending ribs and a shoe comprising 25 two sections having the bases thereof received within the recesses and the body portions thereof fashioned to receive the rail, one of the sections having the base extending beneath the base of the rail and the other of 30 the sections being fastened to the tie by a suitable bolt, the parts being arranged and constructed as hereinafter more particularly described and later pointed out in the appended claims.

Figure 1 represents a perspective view of my invention as it appears in use. Fig. 2 represents an enlarged detailed longitudinal sectional view through the shoe, tie and rail. Fig. 3 represents an enlarged detailed perspective view of the shoe and a portion of the tie.

In the drawing like characters of reference indicate corresponding parts in each figure.

1 and 2 represent the usual rails of a track which rails are connected each by means of one of my shoes 3 to the tie 4. The rails present as is customary heads 5, webs 6 and bases 7.

50 The tie which I prefer to use is of special construction, being formed entirely from metal. It is supplied on the upper side toward the ends with pairs of inner and outer recesses 8 and 9 separated by a cross web 10, these recesses being designed to receive the bases of the shoe sections as later

described. It is to be noticed that the recess 8 has one of the walls thereof inclined to present a wedge or V-shaped groove 11. The remaining walls of both the recesses 8 and 9 are vertical.

The tie is supplied on the under side and toward the ends with pairs of ribs 12 and 13 which have the effect of preventing the tie from creeping endwise when it is laid in the roadway. The shoes 3 are as now described. They comprise each inner and outer sections 14 and 15. The section 14 has the base thereof arranged to pass into the recess 8 in the tie, the said base being supplied with a V-shaped tongue 16 complementary to the V-shaped groove 11. The edge of the base remote from the tongue butts against the web 10 and the adjoining side is recessed at 17 to receive one side of the base of the rail 70 snugly, the recess being deep enough to permit the upper portion of the section to butt against the web 6 of the rail.

The section 15 of the shoe has the base 18 thereof fashioned to pass snugly and 80 squarely into the recess 9 and the body portion thereof extending and shaped to fit over that portion of the base of the rail which is not received within the recess 17. This extending portion also butts up against the 85 web of the rail. When the section 15 is in position it is fastened by a bolt 19 passing through the tie and the said section, the bolt having the head thereof countersunk in the under side of the tie and the upper end 90 thereof threaded and supplied with a nut 21. In order to strengthen the tie it is formed with facial projecting pieces 22 and 23 and it is in these that the recesses 8 and 9 are actually formed.

When a rail is to be secured to the tie the section 14 is inserted with the base thereof within the recess 8. It is necessary in this operation to first insert the tongue within the groove and then swing the opposite side 100 of the section down into position. The rail is then laid, one edge of the base thereof being forced by side movement into the groove 17. It will here be noticed when this is accomplished that the base of the rail rests 105 partially on the base of the said section and on the web 10. The section 15 is then applied, the base 18 thereof being fitted into the recess 9. Upon the screw 19 being then inserted and the nut 21 tightened down the 110 projecting portion of the said section holds the rail securely in position.

It will be seen that owing to the peculiar construction the section 14 requires no fastening as the tongue holds it on one side and the rail bears on it on the other. With my shoe in use it will be impossible for rails to spread as is often the case where spikes are used. The recesses 8 and 9 provide for the lateral stresses on the sections of the shoe as will be readily apparent. It is here 10 pointed out that the shoe when applied on the tie actually presents an aperture having in vertical section a contour complementary to the base of the rail which it is to receive.

15 What I claim as my invention is:—

1. The combination with a tie provided with a pair of adjoining recesses divided by a cross web and a rail provided with the usual base, the width of the web being less 20 than the width of the base of the rail, of a shoe comprising two sections having the bases thereof designed to fit into the recesses aforesaid, one of said shoes being supplied on one side with a groove adapted to 25 receive one side of the base of the rail and the other of said shoes being supplied with an extending portion extending over the remaining side of the base of the rail and releasable means for fastening the latter section 30 to the tie, as and for the purpose specified.

2. The combination with a tie provided with a pair of inner and outer recesses separated by a cross web the inner recess being 35 supplied at the side remote from the web with a V-shaped groove and a rail provided with the usual base, the width of the web aforesaid being less than the width of the rail base, of a shoe formed from inner and outer

sections having their bases passing into the recesses in the tie, the inner section being supplied with a V-shaped tongue designed to enter the V-shaped groove presented by the inner recess and having the body portion thereof provided at the side remote to the tongue with a channel designed to receive one side of the base of the rail and the outer section having an extending portion designed to fit over the remaining side of the rail base and releasable means securing the outer section to the tie, as and for the purpose specified.

3. The combination with a tie having a pair of inner and outer recesses separated by a dividing web and a rail provided with the usual base and having one side of the base resting on the web and the other side extending over a portion of the inner recess, of a shoe formed from an inner and an outer section, the inner section having the base thereof received within the inner recess and passing beneath the overhanging side of the rail base and the body portion thereof passing above the overhanging side aforesaid of the rail base and the outer section having the base thereof passing within the outer recess and the body portion thereof extending over that portion of the rail base riding on the web and a releasable bolt securing the outer section to the tie, as and for the purpose specified.

Signed at Winnipeg this 10th day of July 1913.

WILLIAM EDWARDS.
